CLAIM

The ornamental design for a front panel of a receptacle, as shown and described.

DESCRIPTION

FIG. 1 is an upper perspective view of a front panel of a receptacle, showing the new design.

FIG. 2 is a lower perspective view thereof.

FIG. 3 is a front view thereof.

FIG. 4 is a left side elevational view thereof.

FIG. 5 is a right side elevational view thereof; and, FIG. 6 is a bottom elevational view thereof.

The broken lines shown in the drawings are for illustrative purposes only and form no part of the claimed design. The shading shown in the drawings is provided only to illustrate the contour of the article; it is not indicative of any particular texture.
